APPARATUS FOR SUSPENDING GLASS PLATES

Georges Paul Despret, Paris, France, assignor to
 The American Securit Company, Washington,
 D. C., a corporation of Delaware

Application March 23, 1936, Serial No. 70,479
 In France March 28, 1935

2 Claims. (Cl. 49—14)

During the tempering step of glass plate, sheets or other similar products the sheets are generally suspended at their upper part by grippers of the so-called "frog leg" type, the advantage of this 5 method of suspension consisting in that a very small zone or surface of the sheet is engaged.

The grippers themselves are attached to a support which is generally movable, for example a swingletree bar.

10 The sheets thus suspended are carried into a heating furnace of any suitable construction in which they are carried to a temperature near the softening point. When this temperature has been attained the sheets are withdrawn from 15 the furnace and carried into a cooling apparatus where they are suddenly cooled. In this manner the sheets pass into the so-called tempered state, through which they are given new properties, such as resistance to fracture, to heat, etc.

20 During the operation the glass sheets suspended as before described may become deformed through the action of the heat, particularly if the sheets are of great dimensions.

The present invention relates to a suspension 25 apparatus for glass plate or sheets, panes or similar products, applicable particularly in the tempering operation, for the purpose of preventing deformation or deterioration of the suspended sheet or plate.

30 In accordance with the invention the grippers, preferably of the "frog leg" type are connected to their support or swingletree by means of a resilient device.

35 By means of this resilient device, on release of the gripper support above, in raising the suspended sheet after the heating, the grippers are prevented from closing suddenly, through the action of inertia, due to the mass of the sheet, and sharply impressing their points into the 40 glass, or sheets of other material and thus create deformation in the vicinity of these points. The resilient suspension thus precludes such local deformation.

45 The suspension device is completed preferably by a frame or chassis having rigid sides, intended to encompass temporarily one or more sides of the suspended plate, this frame comprising stop members mounted oppositely in pairs, between 50 which the corresponding edge of the suspended plate engages.

These stops prevent deformation of the sheet during their heating. As known, the heat being concentrated at the centre of the furnace, the 55 glass plates, sheets, etc. have a tendency to de-

form by bulging or torsion. The frame stops thus hold the sheet perfectly flat.

Other features will be apparent from the following description.

On the accompanying drawings, given by way 5 of example:

Figure 1 is a front elevation of the assembled improved suspension device.

Figure 2 is a profile.

Figure 3 is a partial, enlarged section on line 10 3—3 of Fig. 1.

Figures 4 and 5 are partial views, in elevation and plan, of the frame locking device in operative position.

Figure 6 is a partial section on line 6—6 of 15 Fig. 5.

Figure 7 is a diagrammatic front elevation of a modification.

Figure 8 represents two positions of the frame 20 very diagrammatically.

According to the construction illustrated on Figs. 1 to 6, the sheet 1, of glass or other material is suspended by grippers of the "frog leg" type, in which the two jaws are provided with sheet engaging points 3 and are pivoted at 4 to each 25 other, and at 5 and 6 to the arms of a compass 7, so that the whole forms a deformable quadrilateral.

The grippers are suspended by the top of their compass from a swingletree or bar 8 through a 30 resilient device.

In the exemplary embodiment shown each of the precedingly described grippers is connected by a rod 9 to a rod 10, terminating at its lower end in a hook 11 and at its upper end in a shoulder formed, for example, of a washer 12 (Fig. 1). The rod 10 bears through this washer, from 35 above, downwardly on a spring 13 or other resilient or cushioning member. This spring 13, or similar member, is seated in a tube or casing 14 and rests on the base 15 in the lower end of said 40 casing. At the upper end the tube or casing 14 carries a plug 16 which is connected by means of a hook 17 to an attaching member 18 of the swingletree.

45 As previously stated, by means of the resilient suspension described or modifications thereof, when the sheet is raised after being heated, the action of inertia, due to the mass of the plate, is overcome, and thus the grippers are prevented 50 from suddenly closing and forcing their points 3 into the plate to such depth as to cause local deformation.

The mounting described provides resiliency not 55 only vertically, but also torsionally in a horizon-

tal plane, that is, the plate 1 may turn within certain limits about a vertical axis without resultant deformation, as would be the case if the distances ab — $a'b'$ were invariable and equal. In fact, due to the resilient suspension, the attachments connecting the points a , b and a' and b' may vary in length and follow the geometric length variations of the distances ab and $a'b'$, due to said oscillations of sheet 1, thus preventing the application of the entire force of the grippers on the sheet.

This second advantage of the resilient suspension is, also of importance, the device being completed preferably by a frame intended to prevent or minimize all warping of the plate and at the same time any oscillation of the latter, which would cause inconvenience, as described herein-after, at least during the critical period at the beginning of the heating before the tempering. 20 This rigid frame or chassis 19 is formed, for example, by four tubes 19^a braced together pairwise at 20 and connected below by a bar 21 (Figs. 1 to 3).

Affixed to this bar connection 21 are a certain 25 number of guides, which may consist, for example, of simple screws oppositely disposed in supports 23, (Figs. 1 to 3).

Without exceeding the scope of the invention the guides may also be formed of any other similar arrangement, for example, rods carried by screws, etc.

The distance between two opposite screws is regulable according to the thickness of the sheets 1 to be tempered.

35 Each tube 19^a of the frame or chassis 19 may slide in grooves 24 (Figs. 5 and 6) provided in the horizontal frame members of the swingletree 8.

The position of tubes 19^a relative to swingletree 8 may be fixed by any kind of retaining device.

For example, according to the embodiment represented on Figs. 1-4-5-6, the retaining device is formed by the grippers 25 with the retractile spring 26. Grippers 25 are mounted oscillatably 45 at 27 on swingletree 8. It is apparent that through the action of spring 26 the grippers 25 hold the tubes 19^a against the swingletree 8. Notches 28 (Fig. 6) are also provided in the tubes 50 at suitable intervals, so that the frame may remain suspended at different heights relative to the swingletree.

The descent of frame 19 after release from the grippers 25 is limited by stops 40 (Fig. 1), which 55 are regulable in position.

The following is the improved method of heating, in accordance with the invention.

The sheet 1 of glass, plate, or similar material is first hooked to the grippers 2, the frame 19 is 60 then carried into a position such that the bottom of the sheet is engaged between the screws 22.

The sheet 1 thus held by the rigid frame is then lowered into the furnace to be carried therein to the suitable tempering temperature.

65 When the temperature of the sheet has reached a certain value, the order of 450° C. for example I have found that, the tendency of the sheet to deform no longer exists. Thus, when this temperature is attained, the frame is released by 70 manipulating the retaining grippers 25, so as to lower it for a degree regulated by the stops 40, and so that the bottom of the sheet is no longer engaged between stops 22. This release of the chassis is necessary, because if left in its initial 75 position badly tempered zones or nodes would be

produced in the sudden cooling by an air jet, these zones being at the point of screws 22.

On the other hand, notwithstanding that the pressure of the cooling air is exerted on both surfaces in an approximately equal manner, the 5 glass plate oscillates slightly during the cooling, which would bring it in contact with the screws 22 in the form of repeated shocks, which might make impressions or imprints in the glass.

It is evident that other means for preventing 10 deformation of the glass sheet in accordance with the invention may be realized, without departing from the scope thereof; for example, the guides may be distributed not only over the lower strip of the plate, but over the entire periphery. In 15 such case the sheet is released before the tempering by any suitable mechanism.

Figure 7 shows by way of example a mechanism of this type. According thereto the tubes 19^a on each side of the sheet, carrying the guides are 20 pivoted at 29 and 30. Also, two arms 31 and 32, pivoted together at 33, are connected with the tubes 19^a by the pivots 34 and 35.

The chassis 19 is locked against the lower part 25 of swingletree or bar 8 by a locking device 25, of any kind, for example of the type described.

When the chassis 19 is released it opens under the action of a spring 36, for example, which raises the arms 31 and 32 at 31' and 32' (Fig. 8) and removes the guides from the three edges of 30 the sheet. The glass sheet is suspended from the bars 31—32 by the gripping devices 3. Guiding forks or yokes 22 straddle the top edge of the sheet and serve to guide it and maintain it against distortion. When the bars 31—32 are raised the 35 yokes 22 move upwardly to a point above the top edge of the glass sheet. Fig. 8 shows the chassis in the open position. The longitudinal tubes 19 have passed into the position 19'.

It is, of course, to be understood that the invention is not limited to the embodiments illustrated and described, which are given by way of example only.

Having thus described my invention, what I claim is:

1. In apparatus for suspending glass sheets, the combination of a supporting bar, means for suspending the sheet from said bar, a frame associated with said bar provided with a bottom portion, side portions pivoted to the bottom portion, means carried by said frame for maintaining the sheet against lateral movement and means engaging the side portions of the frame for separating the upper end thereof to remove the side portions of the frame out of guiding position in 55 respect to the glass sheet.

2. In apparatus for suspending glass sheets, the combination of a supporting bar, means for suspending the sheet from said bar, a frame associated with said bar and provided with a bottom portion, side portions pivoted to the bottom portion, means carried by said frame for maintaining the sheet against lateral movement, means engaging the side portions of the frame for 60 separating the upper end thereof, means connecting the side portions of the frame above the sheet of glass, glass suspending devices associated with the last named means, and means engaging the side portions of the frame for separating the upper end to remove the side portions 65 of the frame out of guiding position in respect to the glass sheet and to lift the sheet in respect to the bottom portion of the frame.
